United States Patent Office.

J. M. SHUCK, OF OSKALOOSA, IOWA.

Letters Patent No. 90,467, dated May 25, 1869.

IMPROVED WASHING-MACHINE.

The Schedule referred to in these Letters Patent and making part of the same.

To all whom it may concern:

Be it known that I, J. M. SHUCK, of Oskaloosa, in the county of Mahaska, and State of Iowa, have invented a new and useful Improvement in Washing-Machines; and I do hereby declare that the following is a full, clear, and exact description thereof, which will enable others skilled in the art to make and use the same, reference being had to the accompanying drawings, forming part of this specification.

This invention relates to improvements in washing-machines, and consists in the arrangement of a pair of vibrating wash-boards operating in conjunction, the one having a surface corrugated horizontally and vertically, and the other composed of vertical bars arranged at suitable distances apart, the spaces between coinciding with the vertical lines of protuberances on the first-mentioned board.

Figure 1 represents a longitudinal sectional elevation of my improved machine; and

Figure 2 represents a plan view of the same.

Similar letters of reference indicate corresponding parts.

A represents the case, preferably of rectangular form in the horizontal plane, but having a bottom inclined with respect to the horizontal line.

B represents a wash-board, corrugated vertically and horizontally, supported in an edgewise position transversely of the case, and connected to a sliding frame, C, resting on the bottom of the case, and deriving motion from the crank-shaft D.

E represents a wash-board composed of bars F, arranged side by side at regular intervals, and supported at each end by the rails G. The said board is pivoted in the axis of the upper rail G, by the ends thereof, to the sides of the case, on which pivots it is oscillated by a connecting-rod, also operated by the main shaft.

The vertical lines of protuberances of the board B

are coincident with the spaces between the bars F of the board E, and serve to force the water out of the clothes and through the spaces. The horizontal lines of protuberances serve to hold the clothes from sliding upward under the action of the oscillating board, and thus, in conjunction with the latter, cause the clothes to change position by an intermittent rotary motion.

The two boards are so arranged as to have a movement in one direction, in unison, or nearly so, while in the other direction the movement of the board E is more rapid than the other, moving away from it, and taking against the clothes in a new position when starting into the first-mentioned movement, in unison with the board B.

By pivoting the board E at its upper end, and connecting it with the crank-shaft D at the same point, it is enabled to oscillate for the purpose of moving the clothes, and become stationary when the squeezing operation is performed.

I am aware that hinged or pivoted squeezers have heretofore been operated from a double-crank shaft, but in all cases the oscillating squeezer has been hinged at its lower end to the suds-box, and its upper end attached to the connecting-rod from the crank-shaft; both squeezers, therefore, move from and toward each other uniformly.

Having thus described my invention,

I claim as new, and desire to secure by Letters Patent—

The board E, when pivoted at its upper end, and connected to the crank-shaft D at the same point, by means of the pitman H, in combination with the board B, also connected to the crank-shaft D, all operating as described, for the purpose specified.

J. M. SHUCK.
